US00D837173S

(12) **United States Design Patent** (10) **Patent No.:** **US D837,173 S**
Lyngra et al. (45) **Date of Patent:** **** Jan. 1, 2019**

(54) **FREESTANDING COLLABORATION
ENDPOINT**

(71) Applicant: **Cisco Technology, Inc.**, San Jose, CA (US)

(72) Inventors: **Andre Lyngra**, Oslo (NO); **Lars Torbjørn Ormvold**, Sperrebotn (NO); **Stian Akre**, Hvam (NO)

(73) Assignee: **Cisco Technology, Inc.**, San Jose, CA (US)

(**) Term: **15 Years**

(21) Appl. No.: **29/622,388**

(22) Filed: **Oct. 17, 2017**

(51) LOC (11) Cl. **14-03**

(52) U.S. Cl.

USPC **D14/126; D14/239**

(58) **Field of Classification Search**

USPC ..... D14/125-134, 239, 371, 136, 374-377, D14/440, 450, 448, 336, 342, 159; 312/7.2; 348/836, 838, 180, 184, 325, 348/739; 248/917-924, 465; 345/104, 345/133, 156, 168, 87, 173; D21/329, D21/515, 577, 622, 333, 433, 448, 452, D21/450, 331, 505; D10/15, 26; 446/484, 175, 356; D6/477, 479, 300; D20/10, 19, 39; D16/203, 241; 160/24 CPC G06F 1/1601; G06F 1/1643; G06F 1/1652; G06F 1/1647; G06F 3/0412; H05K 5/0004; H05K 5/0017; H05K 5/02; H05K 5/0217; H04N 13/0459

(57) **CLAIM**

The ornamental design for a freestanding collaboration endpoint, as shown and described.

DESCRIPTION

FIG. 1 is a front perspective view of a freestanding collaboration endpoint;

FIG. 2 is a rear perspective view of the freestanding collaboration endpoint of FIG. 1;

FIG. 3 is a front view of the freestanding collaboration endpoint of FIG. 1;

FIG. 4 is a back view of the freestanding collaboration endpoint of FIG. 1;

FIG. 5 is a first side view of the freestanding collaboration endpoint of FIG. 1;

FIG. 6 is a second side view of the freestanding collaboration endpoint of FIG. 1;

FIG. 7 is a top view of the freestanding collaboration endpoint of FIG. 1; and,

FIG. 8 is a bottom view of the freestanding collaboration endpoint of FIG. 1.

Any portions shown using dashed lines are for illustrative purposes only and form no part of the claimed design.

1 Claim, 7 Drawing Sheets
